[57] CLAIM

The ornamental design for a sportsman's towel device, as shown and described.

DESCRIPTION

FIG. 1 is an environmental perspective view of a sportsman's towel device showing my new design;

FIG. 2 is an rear planer view showing the interior pocket of my new design;

FIG. 3 is a right side elevational view with the left side being a mirror image thereof;

FIG. 4 is a rear view thereof;

FIG. 5 is a top view thereof; and,

FIG. 6 is a bottom view thereof.

The broken line showing of a person in FIG. 1 is for illustrative purposes only and forms no part of the claimed design.
